BEET TOPPING MACHINE

Otto H. Block and Nettie A. Block,
Fort Collins, Colo.

Application February 3, 1948, Serial No. 5,996

1 Claim. (Cl. 56—153)

1

This invention relates to improvements in beet topping machines and more particularly to an improved machine for removing the leafy tops of sugar beets and similar plants preparatory to removing the beets from the ground, and for piling the tops of several rows of beets in a windrow from which they may be gathered for use as stock feed or other purposes.

It is among the objects of the invention to provide an improved beet topping machine which can be adjusted to compensate for furrows or ditches of different depth between the beet rows, which is operative to top the beets in two or more rows at the same time and to pile the tops from a large number of beet rows in a single windrow, which may be either self-powered or driven from the power take-off of a towing tractor, and which is simple, durable and economical in construction and easy to adjust and operate.

A somewhat more specific object resides in the provision of an improved beet topping machine including a topping unit operative to cut the tops from at least two rows of beets at one time, an elevator unit pivotally connected to the topping unit to be pulled thereby and operative to place the tops from a number of rows of beets in a single windrow, and a common driving means for the topping and elevator units.

Other objects and advantages will become apparent from a consideration of the following description in conjunction with the accompanying drawings, wherein:

Figure 1 is a side elevation of a beet topping machine illustrative of the invention.

Figure 2 is a top plan view of the machine 35 illustrated in Figure 1.

Figure 3 is an elevation of an extensible driving connection between the topping unit and the elevator unit of the improved beet topping machine.

Figure 4 is a top plan view of the extensible driving connection illustrated in Figure 3.

Figure 5 is a longitudinal cross-section taken substantially in the plane on the section line 5—5 of Figure 2.

Figure 6 is a longitudinal cross-section of the topping unit taken substantially in the plane of section line 6—6 of Figure 2.

Figure 7 is a top plan view of the frame of the topping unit and elevator unit.

Figure 8 is a transverse cross-section of the elevator chute of the elevator unit taken substantially in the plane of the section line 8—8 of Figure 2.

Figure 9 is a cross-section on an enlarged scale

2

showing a structural detail of the machine and taken substantially in the plane of the section line 9—9 of Figure 2.

Figure 10 is a cross-section on an enlarged scale showing a structural detail of the top gathering reel of the machine.

Figure 11 is a cross-section on an enlarged scale showing a structural detail of the cutting blade of the machine; and

10 Figure 12 is a cross-section on an enlarged scale also showing a structural detail of the cutting blade and when viewed from a position substantially at 90 degrees to the position from which the blade structure is viewed in Figure 11.

15 With continued reference to the drawings, the improved beet topping machine comprises a topping unit, generally indicated at A, and an elevator unit, generally indicated at B.

Referring now to Figure 7, the topping unit A 20 has a frame including an elongated axle 10 from the intermediate portion of which a pair of spaced, parallel bars 11 and 12 extend forwardly to carry the top cutting mechanism at the forward ends thereof. A third bar 13 extends forwardly from one end of the axle 10 and is substantially parallel to the bars 11 and 12 and spaced from the bar 11. Suitable rubber tired-wheels 14 are journaled, one on each end of the axle, and a towing hitch socket 15 is secured to the axle substantially at the mid-length position thereof, and extends rearwardly therefrom.

A brace 16 extends diagonally across the space between bars 12 and 11 from the axle shaft end of bar 12 below the intermediate portion of bar 11 and has an angularly disposed portion 17 extending along the side of bar 11 remote from bar 12 and attached thereto by suitable bolts or rivets and held in spaced relation to bar 11 by spacers 18. A pair of U-shaped braces 19 and 20, having

35 their intermediate or bight portions connected together, are connected at their ends to the portion 17 of brace 16 and to the inner side of bar 13 constituting, in effect, a re-inforcing X-frame structure between bars 11 and 13. A transverse frame member 21, substantially parallel to axle 10, is attached to bars 11 and 12 at points intermediate their length and to the end of bar 13 remote from axle 10 and is provided between bars

40 11 and 13 with a series of spaced-apart apertures 22 for the attachment of the draw bar 23 and adjustable draw bar brace 24 which extends diagonally from the outer end of the draw bar to the apertured portion of brace 21 and is formed 45 in two overlapping parts having registerable aper-

55

tures 25 by means of which the length of brace 24 may be adjusted.

A pair of brackets 26 are secured one to the outer side of bar 12 and one to the outer side of bar 13 opposite the respective ends of transverse brace 21 and wheel struts 27 are journaled at their upper ends in these brackets. The lower ends of brackets 27 are preferably bifurcated to provide forks within which respective front wheels 28 are journaled. The bifurcated lower end portions of the struts are disposed at an angle to the portions of the struts journaled in brackets 26 so that the wheels 28 have a castor effect when the frame is moved longitudinally over the ground by a towing device connected to the draw bar 23.

As is also clearly illustrated in Figure 7, the frame of the elevator unit has a transverse rear axle 30 upon the opposite ends of which are journaled suitable rubber tired wheels 31, a reach or tongue 32 disposed at right angles to the axle intermediate the length thereof, and a pair of diagonal braces 33 and 34 extending diagonally from a position near the front or distal end of the reach 32 to positions adjacent the corresponding ends of axle 31. At its forward or distal end reach 32 is provided with a towing ball 35 which is received in the towing socket 15 secured on axle 10 of the topping unit. A pair of adjustable standards 36 extend upwardly from the axle 30 near the opposite ends thereof and are connected at their upper ends by a transverse, normally horizontal bar 37. As shown in Figure 5, each standard 36 is conveniently formed in two parts which overlap and are provided in their overlapping portions with series of apertures 38 through which bolts 39 may be extended to secure the two parts of each standard together in adjusted position relative to each other. The horizontal bar 37 is also provided with a series of longitudinally extending, spaced-apart apertures 40 for a purpose which will presently appear.

Referring now to Figures 1 and 2 it will be noted that the portions of bars 11 and 12 ahead of the brackets 26 are inclined upwardly and forwardly. The topping knife 41 is secured to the bars 11 and 12 immediately ahead of the bracket 26 by suitable depending arms 42 which are rigidly secured one to each end of the knife, or formed integrally therewith, and connected adjacent their upper ends to the bars by suitable fastening elements such as the screws 43. As shown in Figure 11, the lower screw 43 extends through one of a series of spaced-apart apertures 44 in the arm 42 illustrated therein and the upper screw 43 extends through one of a series of spaced-apart elongated slots 45 which extend transversely of the arm. The series of apertures and slots provides means whereby the blade may be adjusted vertically relative to the arms 11 and 12 and the slots 45 provide means whereby the knife may be tilted forwardly or backwardly, as indicated in full and dotted lines in Figure 11, so that the cutting edge of the knife can be adjusted for the depth of the furrows or irrigation ditches in which the wheels travel and positioned closely adjacent the surface of the ground over which the topping machine travels.

The front ends of the bars 11 and 12 are apertured to receive pivot pins 46 pivotally supporting the lower ends of a pair of upstanding links 47 the upper ends of which are apertured and provided with bearings in which a reel shaft 48

is journaled. Links 47 are maintained in upright position by respective adjustable length struts 49 the forward ends of which are pivotally connected to the links intermediate the length thereof and the rear ends of which are pivotally connected to the sides of a chute, generally indicated at 50, supported on the frame of the topping unit.

A reel, generally indicated at 51, is mounted 10 on the shaft 48 and may conveniently comprise a pair of end discs 52 having hubs 53 secured to the centers thereof and receiving the shaft 48, and a plurality of slats 54 extending between the end discs and arranged diagonally or spirally relative to the central shaft 48.

As illustrated in Figure 10, each slat or blade 54 may comprise a wood or metal strip of appropriate dimensions to one side of which a flap 55 of a resilient material, such as rubber, is secured by suitable fastening elements, such as the bolts 56. Reel 51 is of such a diameter and is so mounted relative to the cutting blade 41 as to sweep the beet tops across the cutting edge of the blade so that the blade will sever the tops from the beets as the machine is drawn along the rows of beets. Knife 41 has a length sufficient to extend across at least two adjacent rows of beets and reel 51 has a length substantially the same as that of knife 41. By means of the adjustable length struts 49 the reel may be moved forwardly or rearwardly relative to the knife to accommodate the machine to beet tops of different size.

Chute 40 is of rectangular cross-section and comprises a pair of spaced-apart, substantially parallel side walls 57 the bottom edges of which are connected by transverse bars or braces 58. The front ends of these side walls may be conveniently supported on the front transverse frame member 21 while the rear ends are supported on a U-shaped support 59 the legs of which are connected adjacent their lower ends to the bars 11 and 12 adjacent the rear ends thereof and the bight or intermediate portion 60 of which extends transversely across the bars 11 and 12 above the same and supports the rear ends of the chute side walls 57.

A pair of belt-rollers 61 are rotatably mounted between the side walls 57 one at each end of the chute and an endless, flexible, conveyor belt 62 is carried by these rollers and constitutes the bottom of the chute. This belt has transverse slats 63 thereon at longitudinally spaced intervals to receive the beet tops from the reel 51 and move them from the front to the rear end of the topping unit A.

A platform 64 is supported on the bars 11 and 13 adjacent the axle 10 and a suitable power plant 65, such as a gasoline engine, is mounted on this platform.

The rear belt roller 61 has a shaft 66 extending axially therethrough and journaled in the chute side members 57 which shaft extends outwardly beyond the corresponding side members at both ends thereof. A belt pulley 67 is mounted on the end of shaft 66 adjacent the engine 65 and connected by a belt 68 with a belt pulley 69 on the drive shaft of the engine. Rotation of shaft 66 by the engine will operate the conveyor belt 62 in an obvious manner, the top portion of the belt moving rearwardly of the topping unit from the reel toward the associated elevator unit B.

A second belt pulley 70 is mounted on shaft 56 and is connected by a belt 71 with a belt pulley 72 mounted on the corresponding end of reel

shaft 48 so that the reel 51 will be driven simultaneously with the conveyor belt 62. On smaller size units a suitable gear box may be substituted for the engine or other power plant 65 which gear box may be operatively connected with the power take-off of the towing tractor by a suitable flexible or extensible shaft in a manner well-known to the art.

A pair of diverging guard boards 73 are connected to the forward ends of the chute side members 57 to guide the beet tops to the reel and knife so that they will be severed and directed by the reel onto the belt 62.

The knife 41 as is particularly illustrated in Figure 2, is inclined at a slight angle to the perpendicular with respect to the bars 11 and 12 of the topping unit frame to improve its operation in severing the beet tops as it is drawn into contact with them.

The elevator unit B has a chute, generally indicated at 74, of rectangular cross-section which includes a pair of spaced-apart, substantially parallel side walls 75, the bottom edges of which are connected by spaced-apart transverse slats or braces 76. A supporting beam 77 is secured beneath the forward end of chute 74, substantially medially of the width thereof and extends forwardly of the chute with its front end disposed at an angle to the remainder thereof and pivotally connected to the top of towing bracket 15 so that the rear end of the chute may swing transversely of the elevator unit frame in an arc centered on the pivotal connection 78 between beam 77 and bracket 15. Near its rear end the chute is supported on the transverse, normally horizontal bar 37 of the elevator unit frame and is shiftable lengthwise of this bar when swung about the pivotal connection 78.

A belt roller 79 is journaled in the chute side walls 75 at the forward ends thereof and near the bottom of the chute and a complementary roller 80 is journaled in these walls at the rear ends thereof and also near the bottom edges.

An endless conveyor belt 81 is carried by the rollers 79 and 80 for moving beet tops from the belt 62 up the elevator chute 74 for discharge at the rear end thereof.

Two belt rollers 82 and 83 are also journaled in the side wall 75 of the chute above the rollers 79 and 80 and carry an upper belt 84 which is substantially parallel to and spaced above the belt 81 to assist the belt 81 in carrying the beet tops to the upper, rear end of the chute.

A shaft 85 extends axially through the back roller 79 and projects at one end outside of the corresponding chute side wall 75 where it is provided with a bevelled gear 86. The shaft 66 is provided at the corresponding end with a bevelled gear 87 and the bevelled gears 86 and 87 are drivingly connected by an extensible drive unit generally indicated at 88 and particularly illustrated in Figures 3 and 4.

The projecting end portions of shafts 85 and 66 are journaled in angle brackets 89 and 89' which also journal the hubs of bevelled pinions 90 and 91 which mesh respectively with the gears 86 and 87. An internally grooved shaft 92 is connected to the hub of pinion 90 by a universal joint 93 and an externally splined shaft, telescopically received in tubular shaft 92, is connected to the hub of pinion 91 by a universal joint 95. The shafts 92 and 94 provide a driving connection between pinions 90 and 91 while permitting the pinions to move toward and away from each other and to assume different angular

positions relative to each other. The drive between the shaft 66 and the shaft 85 thus permits the elevator unit to swing about the pivotal towing connection between the reach 32 and bracket 15 without interrupting the drive to the lower elevator unit belt 81.

A shaft 96 extends axially through roller 80 carrying the lower belt at the rear end of chute 74, and has a belt pulley 97 secured on an end thereof projecting beyond one of the side walls 75 of the chute 74. A shaft 98 extends axially through the upper belt roller 83 at the rear end of the chute and carries upon one end extending through the corresponding side wall 75 a belt pulley 99 which is in alignment with the belt pulley 97. A belt 100 connects the pulleys 97 and 99 so that the upper belt 84 is driven whenever the lower belt 81 is driven.

With the above described arrangement, when the engine 65 is in operation and drives the belt 68, the reel 51, the topping unit belt 62, and both the belts 81 and 84 of the elevator unit will be driven. With these components in operation, if the machine is towed along the beet rows the tops will be severed by the blade 41, lifted onto belt 62 by a reel 51, transferred by belt 62 to belt 81 of the elevator unit and raised by belts 81 and 84 to the rear upper end of the elevator unit from which they will be discharged.

The pivotal mounting on the front end of the elevator unit chute permits positioning the rear end of the chute so that beet tops from several adjacent rows can be dropped into a single windrow extending in the same direction as the beet rows.

The elevator unit chute 74 is releasably held in position lengthwise of the horizontal bar 37 by a hook 101 one end of which engages in a selected aperture 40 in the horizontal bar and the other end of which is connected to a staple 102 which is slidably mounted on a rod 103 which extends longitudinally of the chute adjacent the bottom edge thereof and is supported at its ends in angle brackets 104 secured to the corresponding side wall of the chute. The slidable mounting of the staple 102 on the rod 103 compensates for the difference between the arcuate path of travel of the rear portion of the chute and the straight transverse bar 37 so that the hook may be brought into engagement in an aperture 40 regardless of the position of the chute lengthwise of the bar.

The invention may be embodied in other specific forms without departing from the spirit or essential characteristics thereof. The present embodiment is therefore to be considered in all respects as illustrative and not restrictive, the scope of the invention being indicated by the appended claim rather than by the foregoing description, and all changes which come within the meaning and range of equivalency of the claim are therefore intended to be embraced therein.

What is claimed is:

A beet topping machine comprising a frame, wheels supporting said frame, a topping knife disposed transversely of and below said frame, a bracket interconnected between each end of said knife and said frame, said brackets providing adjustment of said knife toward and away from said frame and tilting adjustment of said knife relative to said frame, a reel journaled on said frame above and ahead of said knife, an elevator on said frame rearwardly and upwardly inclined from a location adjacent said knife to receive severed beet tops and move such tops rearwardly and upwardly, and a draw bar adjustably attached to

said frame at one end of said reel, said reel comprising a central shaft, a pair of end discs substantially concentric with and secured to said shaft near respectively opposite ends thereof, a plurality of substantially rigid slats extending between said discs at the edges of the latter, and a flap of resilient material secured to each slat.
